TABLE CONSTRUCTION FOR PAPER DRILLS

Henry C. Nygren, Chicago, Ill., assignor to
 Nygren-Dahly Company, Chicago, Ill., a corporation of Illinois

Application January 23, 1939, Serial No. 252,329

6 Claims. (Cl. 77—63)

My invention relates to a table for paper drills and is particularly adapted for single spindle paper drills wherein paper is drilled for loose-leaf filing or binding purposes, and is adapted to provide means whereby holes through the paper can be accurately positioned and spaced with respect to each other without the necessity of moving and repositioning the paper, as is common with drills of this type used heretofore.

Another and further object of my invention is the provision of a table which is moved quickly and easily to any predetermined position by the operator merely unlatching a release means, thereby securing accuracy and proper spacing of the holes drilled through the paper.

Another and further object of my invention is the provision of a table having means thereon so that the operator by merely unlatching the fastening means of the table allows the table to move to a predetermined position, and when released from this point automatically moves on to another predetermined position, the table being previously adjusted with respect to the spindle on the drill so that the holes are accurately drilled through the paper for filing or binding purposes.

Another and further object of my invention is the provision of a table having a plurality of stops thereon which may be adjustably placed at various positions to provide for the proper positioning of the paper under the drills without the necessity of moving the paper or of holding the table while the drilling operation is being performed, this movement of the table being semi-automatic in character and controlled by a latch within easy reach of the operator whereby the table is moved to the various positions needed for the operation and without any particular attention on the part of the operator after the stops on the table have been properly set and the paper placed in the proper position on the table.

In drilling operations for paper for binding and filing purposes it is necessary that the holes therefor be drilled with absolute accuracy or else there is a large amount of spoilage resulting from the drilling operation. Usually paper in quantities of at least a ream is drilled, and it has been common practice heretofore to place the paper on the table, mark the paper to the proper position for drilling, and thereafter shift the paper under the drill where the holes are desired. Very frequently the paper is moved or the measurements are not placed accurately, or the paper is not jogged evenly, with the result

that the holes are drilled through the paper in the wrong positions and a large quantity of paper is ruined and must be recut or thrown away due to this improper positioning of the holes therein.

With my improved device, if care is exercised in the setting of the machine, the holes will be accurately spaced with respect to each other, as well as accurately positioned in the paper itself, and the paper is not moved after it is placed in position on the table, in which position it is held by guiding means common to devices of this sort.

Another object of my invention is the provision of a shifting table which is easy to install, inexpensive to manufacture, and accurate and simple in its operation.

These and other objects of my invention will be more fully and better understood by reference to the accompanying sheet of drawings, and in which—

Figure 1 is a perspective view of a drilling machine with table applied thereto;

Figure 2 is a top plan view of the machine and table shown in Figure 1;

Figure 3 is a front elevational view of the table;

Figure 4 is an end view of the table looking from left to right;

Figure 5 is a detailed sectional view showing the latching mechanism for holding the table in various adjusted positions;

Figure 6 is a detailed sectional view showing the spring tension means for moving the table; and

Figure 7 is a detailed sectional view showing the mounting of the table on the stand, and also the latch means for holding the table in fixed position.

Referring now specifically to the drawings, and in which like reference characters refer to like parts throughout, a stand 10 is shown having the usual reciprocating drill head 11 mounted thereon to which an electric motor 12 is attached, the rear end of the drill head 11 being slidably mounted in the frame 10. A foot treadle 13 is provided by means of which the drill head and motor are reciprocated in a vertical direction to bring the drill bit into contact with the paper. Extending forward from the frame 10 is a projecting portion 14 having a flat topped projecting portion 15 upon which a plate 16 is mounted in fixed relation with the frame in any approved manner. A frame 17 is provided which has a plurality of rollers 18, 18 mounted therein at the front and rear sides of the table and contact the upper side of the plate 16 along its marginal edges, which forms a track upon which the rollers

run as the reciprocating table moves back and forth.

Strips 19, 19 are provided which extend longitudinally of the frame 17 and pass beneath the plate 16 along its inner and outer marginal edges for the purpose of holding the frame 17 in proper position with respect to the plate 16 and prevent displacement of the table in a vertical direction. Mounted upon the frame 17 is a table top 20 with angles 21 extending around the marginal edge of the table top 20 to provide a finished appearance and give strength for the working operations to be conducted upon the table. Mounted upon the ends 22, 22 of the angles 21 at the rear of the table is a rod 23 upon which a plurality of movable stops 24, 24 are positioned. These stops are clamped to the rod by means of a threaded member 25, with the stops having a slit 26a therein so that they are sufficiently elastic on one side to be clamped around the rod 23 in various adjusted positions. The stops 24 at their sides near the table are beveled as at 24a, to allow the stops 24 to freely pass the latch hereinafter described when the table is moved from left to right position.

Secured to the projecting portion 14 of the frame 10 is a bracket 26 having a latch 27 slidably mounted therein. A pin 28 is provided over which one end of a spring 29 is fitted, the opposite end of the spring being secured to a post 30 extending downward from the bracket 26. The latch 27 has a recess 31 in the upper side thereof within which a rocking bar 32 is fitted, the bar being pivotally secured at each of its ends to the projecting rear corner portions of the frame 17 by means of pins 33 at the upper side of and in each end of the bar 32. A lever 34 is provided having its inner end secured to the lower edge of the bar 32 by a pin 35, and its outer end secured to a fingerpiece 36 having a handle portion 37. The fingerpiece 36 is pivotally mounted on one of the angles 21 by means of a rivet 38, and provides means by which the operator can rock the bar 32, thereby withdrawing the latch member clear of the stops 24, 24 carried by the rod 23 on the table 20.

A drum 39 is provided mounted upon an axle 40 carried by brackets 41, 41 secured to the under side of the plate 16 in any approved manner. The drum has a spring 42 coiled therein, one end of which is anchored to a stud 43 carried by the axle 40 and the other end anchored to a pin 44 extending through the drum 39. A tape or strap 45 is wound around the outer periphery of the drum and has its end secured thereto in any approved manner, with its free end secured to the underside of the frame 17 by a bolt 46 or any other approved clamping means.

On the outer end of the axle 40 is a thumb nut 47 having a recess extending longitudinally thereof within which a spring 48 is positioned, with a cap 49 being provided to hold the spring in proper position around the axle 40. The thumb nut 47 has a keyway 50 therein with a key 51 being provided which is seated in the axle 40 and extends up into the keyway 50. The key 51 provides means by which the axle 40 may be rotated by the operator to secure the proper tension on the spring 42 to move the table during the operation of the drill. A recess 52 is provided in one of the brackets 41 within which a key 53 extends, the key being in fixed position with respect to the thumb nut 47, and serves to hold the axle 40 against rotation, thereby hold-

ing the spring 42 in proper tension to move the table upon its being released by the operator by rocking the bar 32.

A stop 54 is provided having an upturned end 55 against which a stop 56 abuts and which prevents the table 20 from overrunning the plate 16 in a right to left direction. The table 20 is prevented from overrunning the plate 17 in a left to right direction by the bracket 26 engaging the angle 21 at the left side of the table 20. Secured to the outer side of the member 17 is a bracket 57 having a locking bolt 58 mounted therein, on the outer end of which a thumb nut 59 is mounted. The bracket 57 has a recess therein within which a spring 60 is positioned around the locking bolt 58, with a pin 61 extending through the locking bolt 58 and projecting laterally therefrom on each side adapted to be moved in recesses 62 on each side of the bracket 57. The inner end of the locking bolt 58 extends into a hole 63 formed in a bracket 64 mounted on the under side of the plate 16, this combination providing means by which the table may be locked in a central position with respect to the drill head 11 for performing fixed operations in paper laid upon the table 20.

A guide bar 65 extends longitudinally of the table and has guide blocks 66, 66 adjustably positioned thereon by means of screws 67, 67, the guide bar at each of its ends being clamped by bolts 68, 68 having thumb nuts 69, 69 thereon. A marginal edge of one of the angles 21 is calipered to assist the operator in the proper adjustment of the abutting stops 66, 66 with relation to the edge of the paper. The table 20 has a groove 70 therein within which a bolt 71 is mounted having a thumb nut 72 thereon by means of which a stop 73 is positioned at the top of the table and against which the ends of the paper is abutted during the drilling operation.

In the operation of the device when it is desired to drill spaced holes in a plurality of sheets of paper, such as a ream or the like, the paper is placed flatwise on the table 20 and in side to side relation with the edge guide blocks 66, 66 and in relation with the end stop 73. The stops 24 are then set at the proper position with respect to the location at which it is desired to drill the holes in the paper. The calipered rear edge of the table provides means for locating the stops at the proper place on the rod 23. If three holes are to be drilled only three stops are needed. After proper adjustment the table is pushed to the left side as far as it will go, the angular end of the latch 27 allowing the stops, because of their angular position, to pass freely past the latch in a left to right direction of the table. Thereafter the operator releases the latch by squeezing upward on the fingerpiece 37, and upon releasing it the table travels to the proper position for a hole to be drilled. The operator thereupon presses downward upon the treadle 13 with his foot, bringing the drill downward into contact with the paper and drilling a hole therethrough. The release is operated again by the operator for the second hole, and the table travels to the proper position. The treadle is again pressed downward and the operation repeated. This can be done, of course, as many times as may be necessary to drill holes in the paper, and once the table is set in proper adjustment it is not necessary to move it for that operation, the operator simply being careful that the paper is placed in proper position against the marginal and end

stops on the table. In this manner, repeated operations of the device can be carried on with the assurance that holes drilled through the paper will be in absolute register and in this manner wastage or spoilage of paper is avoided.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. In combination with a paper drilling mechanism of a movable table, spring mechanism for moving the table in one direction, movable stops carried by the said table, a rod carried by said table, a plurality of movable stops thereon, a latch carried by the said frame, a rocking bar in engagement with the said latch, and manual operable means to actuate the rocking bar whereby the said latch is released from said movable stops.

2. In combination with a paper drilling mechanism of a movable table, spring mechanism for moving the table in one direction, movable stops carried by the said table, a rod carried by said table, a plurality of movable stops thereon, a latch bar having a recess in one end thereof, a rocking bar carried by said table and mounted in the recess in the said latch bar, an operating rod connected to said rocking bar, and an operating handle mounted on the table adjacent the front edge thereof connected to the said operating rod.

3. In combination with a paper drilling mechanism of a movable table, spring mechanism for moving the table in one direction, movable stops carried by the said table, a rod carried by said table, a plurality of movable stops thereon, a latch bar having a recess in one end thereof, a rocking bar carried by said table and mounted in the recess in the said latch bar, an operating rod connected to said rocking bar, and an operating handle mounted on the under side of said table at one side thereof and extending to the front edge thereof connected to the said operating rod.

4. In combination with a paper drilling mechanism having a frame mounted thereon, a table movably mounted on the said frame, a rod at the rear of said table, a plurality of stops movably mounted in the said rod and adapted to be clamped thereto in a plurality of positions, a spring normally under tension, flexible means connecting said spring and the table, a latch slidably mounted on the said frame, a rocking bar carried by the movable table, and manually operable means on the said table whereby the rocking bar may be actuated thereby releasing the said latch from engagement with any one of the said stops.

5. In combination with a paper drilling mechanism having a frame mounted thereon, a table movably mounted on the said frame, a rod at the rear of said table, a plurality of stops movably mounted in the said rod and adapted to be clamped thereto in a plurality of positions, a spring normally under tension, flexible means connecting said spring and the table, a latch slidably mounted on the said frame, a rocking bar carried by the movable table, and manually operable means on the said table whereby the rocking bar may be actuated thereby releasing the said latch from engagement with any one of the said stops, the table being normally movable in one direction and held against movement in the opposite direction until released from the said stops.

6. In combination with a paper drilling mechanism having a frame mounted thereon, a table movably mounted on the said frame, a rod at the rear of said table, a plurality of stops angularly shaped at one of their ends movably mounted in the said rod and adapted to be clamped thereto in a plurality of positions, a spring normally under tension, flexible means connecting said spring and the table, a latch slidably mounted on the said frame, a rocking bar carried by the movable table, and manually operable means on the said table whereby the rocking bar may be actuated thereby releasing the said latch from engagement with any one of the said stops.

HENRY C. NYGREN.
